DESIGN FOR A CLOSURE CAP

William B. Johnson, Easley, S. C.

Application October 11, 1944, Serial No. 115,715

Term of patent 14 years

(Cl. D58—26)

To all whom it may concern:

Be it known that I, William B. Johnson, United States Army, a citizen of the United States, residing at Easley, Pickens County, State of South Carolina, have invented a new, original, and ornamental Design for a Closure Cap, of which the following is a specification, reference being had to the accompanying drawing, forming a part thereof.

I claim:

The ornamental design for a closure cap, as shown.

WILLIAM B. JOHNSON.
